UNITED STATES PATENT OFFICE.

WILLIAM L. MILLER, OF VAN BUREN, INDIANA.

BROADCAST SEED-SOWER.

SPECIFICATION forming part of Letters Patent No. 367,830, dated August 9, 1887.

Application filed October 21, 1886. Serial No. 216,867. (No model.)

To all whom it may concern:

Be it known that I, WILLIAM L. MILLER, a citizen of the United States, residing at Van Buren, in the county of Grant and State of Indiana, have invented a new and useful Improvement in Broadcast Seed-Sowers, of which the following is a specification.

My invention relates to an improvement in broadcast seed-sowers; and it consists in the peculiar construction and combination of devices, that will be more fully set forth hereinafter, and particularly pointed out in the claims.

In the drawings, Figure 1 is a side elevation of a broadcaster embodying my improvements. Fig. 2 is a vertical longitudinal sectional view of the same. Fig. 3 is a transverse sectional view. Fig. 4 is an inverted plan view of the same. Fig. 5 is a detailed perspective view 20 of the centrifugal seed-wheel.

A represents a box or case of suitable dimensions, which is provided on its upper side with a hopper, B, the lower side of which is inclined, as shown. To the upper edge of the hopper is attached the lower end of a bottomless sack, D, which is adapted to receive a suitable quantity of seeds and feed them to the hopper. A strap, E, is attached to opposite corners of the front and rear ends of the box or case, and is adapted to pass over the shoulders of the operator and thereby support the seed-sowing machine.

F represents a transverse shaft, which is journaled under the discharge opening of the hopper, and is provided at one end with a crank, G, and at the opposite end with a spur-wheel, H. The shaft F is squared, and on the same is secured a force-feed seed-wheel, I, which is adapted to slide laterally on the shaft. A circular case, K, depends from the bottom of the hopper and communicates with the discharge-opening thereof, and the said circular case has a discharge-opening on its rear side. The seed-wheel is adapted to move in or out 45 of the case K when it is caused to slide from the shaft F.

M represents a hollow cylindrical sleeve, one end of which is journaled on a projecting flange at one end of the feed-wheel, and the 50 said sleeve is provided with longitudinal ra-

dial flanges on its outer side, which fit in recesses made in one end of the case K. Collars N are fitted on the shaft F and are free to slide thereon and bear against the outer ends of the force-feed seed-wheel and the sliding sleeve. A lever, O, is pivoted under the upper side of the case or box, and has diverging arms at its inner end, which are connected to the sliding collars N. The outer end of the said lever is pointed to form an index, and sweeps over the graduated scale P under the top of the box or case.

R represents a slotted plate, which is secured in a countersunk opening made in the under side of the box or case, and in the said slot 65 works a headed screw, S, the stem of which passes through an opening in the lever O, and is provided with a thumb-nut, T. By means of this thumb-nut the lever may be clamped at any desired position, and thus cause the 70 seed-wheel to be maintained either with its entire length under the discharge-opening in the hopper and in the case K, or partly moved outwardly from the said case, so that only a portion of it will be under the discharge-opening 75 of the hopper, and thereby the quantity of seeds which will be ejected from the hopper when the seed-wheel is rotated may be regulated at will. A spout, U, is attached to the under side of the box or frame A, and is 80 adapted to receive the seeds which are thrown from the discharge-opening of the case K.

V represents a transverse shaft, which is journaled near one end of the box or frame A, and is provided with a gear-pinion, W, 85 which meshes with the gear-wheel H. Near the center of the shaft V is attached a miter gear-wheel, X.

Y represents a vertical shaft, which is journaled near the front end of the box or frame A, and is provided at its upper end with a mitered pinion, Z, that meshes with the wheel X. a represents a concavo-convex seed-disk, which is secured to the lower end of the shaft Y, and is provided with vertical radial wings 95 or flanges b, which project beyond the edge of the seed-disk, and have their upper sides curved forwardly in the direction in which the seed-disk rotates, as shown.

When the crank is turned, the shaft F causes 100

the force-feed seed-wheel to rotate under the discharge-opening in the hopper, so as to convey the seeds therefrom to the spout U, and the shafts V and Y are rotated at a higher rate of speed than the shaft F. This causes the seed-disk a, which is secured to the shaft Y, to whirl very rapidly, and thereby throw the seeds which fall upon it from the spout U by centrifugal force to a considerable distance from the machine and scatter them evenly over a considerable area. The upper curved edges of the wings of the seed-disk catch the seeds as they are projected radially by the centrifugal action of the seed-disk and insure their being thrown to a considerable distance from the machine.

By graduating the scale P and noting the quantity of seeds which are ejected from the hopper when the seed-wheel has its entire surface presented below the discharge-opening thereof and is rotated at maximum speed, the lever O may be moved so as to cause only a sufficient portion of the seed-wheel to operate under the discharge-opening of the hopper to cause the seed to be sowed in any desired quantity to the acre.

Having thus described my invention, I claim—

1. The combination, in a broadcast seed-sowing machine, of the hopper, the force-feed seed-wheel, the shaft F to rotate the latter, and the seed-disk a, geared to the shaft F and adapted to catch the seeds as they fall from the seed-wheel, for the purpose set forth, substantially as described. 35

2. The combination of the horizontally-rotating disk with the force-feed seed-wheel to feed the seeds to the disk, and the hopper having the discharge-opening provided with the case K, in which the force-feed wheel rotates, the latter being movable in and out of the said case, for the purpose set forth, substantially as described.

In testimony that I claim the foregoing as my own I have hereto affixed my signature in presence of two witnesses.

WILLIAM L. MILLER.
